UNITED STATES PATENT OFFICE.

PHILLIP HIEN, OF CHICAGO, ILLINOIS, ASSIGNOR TO DAVID S. WEGG, OF CHICAGO, ILLINOIS.

CAR-COUPING.

SPECIFICATION forming part of Letters Patent No. 746,079, dated December 8, 1903.

Application filed September 10, 1900. Serial No. 29,523. (No model.)

To all whom it may concern:

Be it known that I, PHILLIP HIEN, a citizen of the United States, residing at Chicago, in the county of Cook and State of Illinois, 5 have invented new and useful Improvements in Car-Couplers, of which the following is a full, clear, and exact description, reference being had to the accompanying drawings, and to the letters of reference marked thereon, 10 which form a part of this specification.

This invention relates to car-couplers of that class known as the "Janney" or "Master Car-Builders" coupler. Heretofore in inventions of this class, the draft being en- 15 tirely on the pin whereby said knuckle is pivoted in the draw-head, the breaking of said pin or the jolting of the same out of its seat in the draw-head has caused the train to break in two, frequently causing serious ac- 20 cidents and endangering life and property.

My invention contemplates, together with other important improvements, means for locking the tail of the knuckle in the draw- 25 head in such a manner that the pivot-pin may be entirely removed without the train break- ing in two.

The invention consists in the matters hereinafter described, and more fully pointed out and defined in the appended claims.

30 In the drawings, Figure 1 is a top plan view of a car-coupler embodying my invention. Fig. 2 is a side elevation of the same. Fig. 3 is a horizontal section of the same. Fig. 4 is a section taken on line 4-4 of Fig. 3. Fig. 35 5 is a vertical section of a coupler, taken on line 5-5 of Fig. 3. Fig. 6 is a view similar to Fig. 5, showing the coupling-pin elevated. Fig. 7 is a view similar to Fig. 3 and showing the knuckle in its uncoupled or retracted po- 40 sition. Fig. 8 is a section of the same, taken on line 8-8 of Fig. 7. Fig. 9 is a side eleva- 45 tion of the locking-pin in its elevated po- sition and supported upon the pendulum- dog. Fig. 10 is a view of the same in rear elevation. Fig. 11 is a view similar to Fig. 10, showing the position the parts assume when the knuckle-tail swings outwardly and supports the locking-pin. Fig. 12 is a per- 50 spective view of a stop embodied in my in- vention. Fig. 13 is a top plan view of the

lock to the lock. Fig. 14 is a side elevation of the top of the locking-pin, showing the lock to the lock in its locking position.

As shown in said drawings, A indicates a draw-head of the familiar Master Car-Build- 55 ers' type.

B indicates the jaw of the swinging knuckle, also of the Master Car-Builders' type and similarly pivoted in the draw-head by means of a pivot-pin C.

D indicates a locking-pin extending down- 60 wardly within the draw-head through an ap- erture through the top thereof.

The knuckle of said coupler is provided with a tail B', extending within the draw- 65 head at approximately right angles with the jaw B. Said tail B', as shown, is relatively thin vertically at its rear or inner end and broad horizontally and is provided on its back or outer side intermediate of the pivot and 70 the rear extremity of the same with a later- 75 ally and forwardly directed integral hook b, which is adapted when the knuckle is in its closed or coupled position to interlock with a complementary projection a on the inner wall of the draw-head, as indicated in Fig. 3. On the inner side of said tail approximately opposite the hook b is provided a vertical sur- 80 face, herein shown as plane and approxi- mately parallel with the vertical axis of the tail, against which the locking-pin D engages when the knuckle is in its coupled position, with the effect of locking the hook of the knuckle-tail into engagement with the com- 85plementary projection a on the draw-head, as indicated in Figs. 3 and 5.

As shown, the draw-head is materially re- 90 duced in weight, while retaining the maximum of strength, by coring out the interior of the same in a familiar manner and provid- 95 ing integral strengthening-webs, as more particularly indicated in Figs. 3 and 7. If constructed in this manner instead of cast solid, as obviously could be the case, such webs will preferably surround the aperture for the locking-pin and extend downwardly within the coupler-head into close proximity to the knuckle-tail. Such webs are herein indicated by a'. The bottom of the draw-head is also provided with webs, of which those indicated 100

by a^2 a^3 are transverse of the draw-head, of such height as to permit the knuckle-tail to swing over the same and of sufficient length as to form stops or lateral support for the 5 lower end of the locking-pin D, as indicated in Fig. 5, when the knuckle is in its locked or coupled position.

For the purpose of supporting the locking-pin in its elevated position, or that in which 10 it is out of engagement with the knuckle-tail, I have provided a gravity-acting or pendulum dog E, pivoted in the top of the draw-head and provided at its lower end with the head e, adapted to engage the lower end of 15 the locking-pin when the same is in its elevated position, as indicated more particularly in Figs. 9, 10, and 11, in which the dotted line indicates the upper surface of the knuckle-tail. As shown, the locking-pin D is provided on its side thereof opposite the tail with a longitudinal groove and is made wider at its lower than at its upper end. The stop 20 E' is adapted to fit in the aperture in the draw-head at the side of said locking-pin 25 and is provided with a tongue adapted to close the groove of said pin to prevent rain or snow finding its way within the coupler therethrough. Said stop is provided on its under side with a transversely-apertured lug which 30 depends therefrom adjacent to the groove of the locking-pin, and said pendulum-dog is pivoted to said lug by a pivot-pin E², which, as shown, passes through side flanges surrounding the locking-pin on the top of the 35 draw-head and is secured therein by means of a cotter-pin or other suitable device, herein indicated by e'. The length of said pendulum-dog is such as to permit the head e thereof to depend in the line of movement of 40 the knuckle-tail and to be knocked out of engagement with said locking-pin thereby as the knuckle-tail swings outwardly to its uncoupled position, thereby permitting the locking-pin supported on said head e to drop upon 45 the knuckle-tail, as indicated in Figs. 7 and 8, and to ride thereon until the knuckle is again swung inwardly to its coupled position, when the locking-pin drops downwardly to lock the knuckle, as before described. For 50 the purpose of preventing said pin from being jarred out of engagement with the head e of said pendulum-dog the upper surface of the head of the dog inclines downwardly away from the knuckle-tail. The lower end 55 of the locking-pin D is complementally inclined, so that when the pin is lifted and the head of the dog swings beneath the same the weight of said pin resting thereon, as indicated in Fig. 10, acts to hold said parts in engagement until the dog is knocked from 60 beneath the same, as before described.

In car-couplers of this class it is important that means be provided for limiting the outward swing of the knuckle to hold the relatively wide tail in a position to project well out into the space between the draw-head and the knuckle, so that the opposing coupler in

the act of coupling will engage this tail and push the same back into locked position, and to prevent the locking-pin coming down behind the tail, and thus locking the knuckle in its open or uncoupled position. For this purpose I have provided at the extremity of the knuckle-tail, on the rear side of the same, an integral rearwardly-extending projection b², 70 adapted to engage an upwardly-projecting web a³, integral with the bottom of the coupler or draw-head, as shown in Figs. 7 and 8. As shown, the knuckle-tail is provided on its upper side with a rearwardly-extending lip or 75 flange b³, adapted to receive and support the locking-pin during the outward swing of the knuckle. The front end of the draw-head is provided with a relatively narrow slot at the side opposite the pivot-pin to receive said 80 lip or flange. Obviously, if preferred, the knuckle-tail may be made longer than herein shown, and said lip or flange may be omitted. When constructed in this manner, however, it necessitates the cutting away of the front 85 end of the draw-head to a greater extent than when the lip or flange is used and for that reason is not herein shown.

For the purpose of preventing the locking-pin from creeping upwardly with the motion 90 of the car I have provided means for locking the same in its locking position, which I term a "lock to the lock," as indicated in Figs. 1, 2, 9, 10, 11, and 14. Said lock to the lock consists, as shown, of a clevis G, pivoted to 95 the outer apertured end d of the locking-pin by means of a pin g passing through the apertured ends of said clevis and the aperture in said end d of said locking-pin and secured 100 therein by a cotter-pin or other suitable 105 means. Said clevis is provided on one side thereof with a laterally and rearwardly directed hooked arm G'. Any desired means for lifting the locking-pin may be employed, but preferably the familiar devices secured 110 to the car end, comprising a bell-crank provided with a chain one end of which is secured in said clevis, as shown in Figs. 1, 2, 10, and 14. On the top of the draw-head is provided a laterally and rearwardly directed 115 horizontal flange e² in position to be engaged to the hooked arm G' when the pin is in its locking position, at which time the clevis falls to the position indicated in Figs. 1, 2, and 14, thereby effectually locking the locking- 120 pin from being raised. When it is desired to lift the locking-pin, the clevis is first raised by means of the chain or otherwise, thereby swinging the hook of the arm G' out of engagement with the flange e² and permitting 125 the lifting of said locking-pin. For the purpose of preventing the clevis falling over when elevated the lower ends of the same are provided with projections g' g', which engage the head of the locking-pin before the 130 clevis reaches a vertical position, thereby insuring that the weight of the clevis and arm G', together with the chain end, will cause said clevis to fall to its locking position.

Obviously, many of the details of construction may be modified without departing from the spirit of my invention.

I claim as my invention—

5. 1. In a car-coupler, the combination with a draw-head, of a knuckle pivotally supported therein, a sliding locking-pin for said knuckle having a laterally-projecting portion, a pendulum-dog depending from a pivotal point in
10 the path of movement of said laterally-projecting portion on the locking-pin and adapted when the locking-pin is elevated to swing by gravity under and support said locking-pin, said dog extending into the path of the tailpiece of the knuckle and adapted to be engaged thereby and removed from beneath the locking-pin when the knuckle is opened, said pin dropping upon and being supported by the tailpiece when the pivoted dog is removed from beneath the same, the pendulum-dog being held by the tailpiece out of contact with the pin until the tailpiece is closed when the dog swings into engagement with the side of said pin and is thereby prevented from interfering with the dropping of the pin into its locking position; substantially as described. 70
- 15 2. In a car-coupler, the combination with a draw-head, of a knuckle pivotally supported therein, a vertically-sliding locking-pin the under surface of the lower end thereof being upwardly inclined, a pendulum-dog pivoted in the upper part of the draw-head to swing toward said locking-pin, and a projection on the lower end of said dog having an upper face inclined toward the locking-pin and adapted to swing by gravity under the latter so as to be engaged by the inclined lower end of the locking-pin to support the latter. 75
- 20 3. In a car-coupler, the combination with a draw-head, of a knuckle pivotally supported therein, a vertically-sliding locking-pin having a longitudinal groove in one side extending to the lower end thereof, a pendulum-dog in the upper part of the draw-head pivoted to swing in the plane of said groove, and a projection on the lower end of said pendulum-dog, whereby when the locking-pin is elevated the dog swings by gravity into said groove thereby permitting said projection to extend beneath the lower end of the locking-pin to support the latter. 80
- 25 4. In a car-coupler, the combination with a draw-head, of a knuckle pivotally supported therein, a vertically-sliding locking-pin having a groove in one side extending to the lower end thereof, a pendulum-dog in the upper part of the draw-head pivoted to swing in the plane of said groove, and lateral projections on the lower end of said dog of greater extent than the width of said groove whereby when the locking-pin is elevated the pendulum-dog swings by gravity into said groove thereby permitting said lateral projections to extend beneath said pin at either side of the groove therein. 85
- 30 5. In a car-coupler, the combination with a draw-head having an opening in the top for a locking-pin, a knuckle, a locking-pin working in said opening, a stop for the pin secured to the draw-head over said opening, a pendulum-supporting dog for the locking-pin pivoted to said stop and having a part adapted when the knuckle is in its closed position to swing under and engage a part of the pin, substantially as described. 90
- 35 6. In a car-coupler, the combination with a draw-head having an opening in the top for a locking-pin, of a knuckle, a locking-pin working in said opening, and having a longitudinal channel therein, a stop for the pin secured to the draw-head over said opening and having a tongue working in said channel in the pin and also having a depending lug, and a pendulum-supporting dog for said locking-pin pivoted to said lug and adapted to engage a part of said pin, substantially as described. 95
- 40 7. In a car-coupler, the combination with the draw-head having an opening in the top, of a knuckle, a locking-pin therefor working in said opening and having a longitudinal channel and also having an enlarged lower end, and a stop for said pin secured to said draw-head over said opening and having a tongue working in said channel and adapted to engage the enlarged lower end of the pin to prevent its withdrawal from the opening, substantially as described. 100
- 45 8. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, and a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 105
- 50 9. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 110
- 55 10. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 115
- 60 11. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 120
- 65 12. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 125
- 70 13. In a car-coupler, the combination with a coupler-head having a vertical opening therethrough and having a laterally-projecting lug on the top thereof at one side of the vertical opening, of a knuckle pivotally mounted in the coupler-head, a vertically-sliding locking-pin located in the vertical opening in the coupler-head and having a lug on its upper end, a U-shaped clevis the ends of which are located on opposite sides of and are pivoted to said lug on the locking-pin, thereby affording means for lifting the pin, a hooked arm rigid with the clevis extending from one of the sides thereof between its upper end and its pivot transversely to the plane of movement of the clevis and adapted to positively engage said lug on the coupler-head when the locking-pin is in its locking position, substantially as described. 130

locking-pin is in its locking position, and a projection on one end of said clevis adapted to engage the top of the locking-pin before said clevis assumes a vertical position, substantially as described.

10. In a car-coupler, the combination with a draw-head, of a knuckle pivotally mounted therein, a sliding locking-pin for said knuckle having a laterally-projecting portion, a pen-
15 dulum-dog depending from a pivotal point in the path of movement of said laterally-projecting portion on the locking-pin, said dog adapted when the locking-pin is elevated to swing by gravity under and support the same.

15. 11. In a car-coupler, the combination with the draw-head, of a knuckle therein, a pin adapted to lock said knuckle in its closed position, said knuckle having a tailpiece provided with a flange for supporting said locking-pin, and a stop beneath the flange, said flange working in a recess in the draw-head of less width than the recess in which the body of the tailpiece works and said stop being adapted to engage a shoulder formed in
25 the draw-head between the narrow and wide

recesses and thereby prevent the flange from swinging out from beneath the locking-pin when the knuckle is opened, substantially as described.

12. In a car-coupler, the combination with 30 a draw-head, of a knuckle pivotally supported therein, a vertically-sliding pin adapted to lock said knuckle in its closed position, a flange extending horizontally from the end of the tail of said knuckle, a stop beneath the 35 rear end of said flange formed by cutting away said tailpiece beneath said flange, said stop adapted to engage a shoulder on the draw-head formed between the openings therein for the tailpiece and said flange and thereby prevent the flange from swinging out from beneath the locking-pin when the knuckle is opened.

In testimony whereof I have hereunto subscribed my name in the presence of two sub- 45 scribing witnesses.

PHILLIP HIEN.
